UNITED STATES PATENT OFFICE.

WILLIAM E. WHITE, OF CHICAGO, ILLINOIS, ASSIGNOR TO KALMAN STEEL COMPANY, OF CHICAGO, ILLINOIS, A CORPORATION OF DELAWARE.

CAGING.

Application filed January 3, 1927. Serial No. 158,625.

My invention relates to an improvement in reinforcements for the plastic covering of beams and other structural shapes.

It is customary, and in fact essential, 5 where beams, columns and similar structural members are enclosed in concrete, to provide a network of wire around the beams, the wire acting as a reinforcement for the plastic material. In common practice, the 10 beam is covered with a section of wire netting, that is, wire in mesh form, similar to woven wire fencing. This however, is unsatisfactory, and requires considerable time for installation.

15 My invention contemplates the employment of a single length of wire having flange-engaging hooks at intervals thereon adapting it to be quickly and simply installed by the use of no tools other than the 20 hands of a single workman, and which shall be retained in position by the resiliency of the wire. As an additional feature of importance, I provide integral projections from the wire extending laterally from the 25 plane of the finished caging, said projections acting as a permanent and accurate means for spacing the forms away from the beams.

The advantages of a construction such as 30 described are many; the structure may be formed by ordinary machines; it is easily handled and shipped, the structure being straight except for the engaging hooks formed at intervals therein, and is quickly 35 applied.

The invention will be more readily understood by reference to the accompanying drawings, in which;

Fig. 1 is a side elevation of a beam to 40 which my improved caging has been applied;

Fig. 2 is an end view thereof;

Fig. 3 is a bottom plan view;

Fig. 4 is a plan view of a length of wire 45 prior to installation, and;

Fig. 5 is an enlarged perspective view of that portion of the wire which includes the engaging hooks and the form spacing elements.

50 The structural member A, here illustrated is of I-beam form and may be a column or girder, or may be of other cross-sectional shape. The caging or reinforcement consists of a single length of wire having straight 55 intermediate portions, 10, and intervening,

spaced hooks, and projections. The projections are formed by means of the lateral bends, 11, the rebent portions, 12, being extended beyond the plane of the straight portions, 10, such portions constituting a loop, 60 13, which is formed into a hook having a horizontal recess or flange engaging space, 14. The structure is best illustrated in its installed position in Fig. 2, in which it is apparent that the hooks, 13, securely engage 65 the flanges of the beam, while the projection serves to space away the form boards, 15.

In order to install the structure, the first 70 two hooks at an end of the straight structure are caused to engage opposite flanges of the beam, and the successive portions are then deflected in a zig-zag manner so that alternate hooks are successively caused to engage opposite sides of the beam flanges. 75 The natural resiliency of the wire serves to retain the structure in position prior to the pouring of the concrete.

Obviously the construction is capable of 80 considerable modification, and I do not wish to be limited except as indicated in the appended claims.

I claim:

1. A beam casing, comprising a single 85 length of wire bent to provide a series of spaced flange-engaging and form-spacing devices therein, each of said devices including a loop projecting laterally from the wire in one direction and a second loop projecting laterally in the opposite direction, a hook being formed in the last named loop and constituting the flange-engaging means, the length of wire occupying a position midway between the extremities of the two loops and spaced away from the face of 90 the beam.

2. A beam caging, comprising a single 95 length of wire bent to provide a series of spaced flange-engaging and form spacing devices therein, each of said devices including a loop projecting laterally from the wire in one direction and a second loop projecting laterally in the opposite direction, a hook being formed in the last mentioned loop and constituting the flange engaging means, said 100 length of wire being normally straight and being bent into zigzag form with alternate hooks engaging opposite flanges of a beam,

the length of wire occupying a position midway between the extremities of the two 105 110

loops and spaced away from the face of the beam.

3. A wire caging for beams, comprising a single length of wire, consisting of 5 straight, parallel portions and intervening attaching and form-spacing portions formed from the length of wire, the spacing portions being in the form of loops projecting at right angles from the line of the straight portions and the attaching portions being in 10 the form of long loops projecting at right angles from the straight portions in an oppo-

site direction to the spacing portions, a hook being formed in the extremities of the loops, the hooks being spaced away from the straight portion whereby the straight portions will occupy a plane midway between the hooks and the extremities of the spacing portions, and spaced away from the adjacent face of a beam.

20 In testimony whereof I have affixed my signature.

WILLIAM E. WHITE.
